DESIGN FOR A DECORATIVE COVER FOR BOTTLES

Franz Koenigsberger, New York, N. Y.

Application December 4, 1945, Serial No. 124,332

Term of patent 3½ years

(Cl. D58—11)

To all whom it may concern:

Be it known that I, Franz Koenigsberger, a citizen of the United States of America, residing in New York city, county of New York, and State of New York, have invented a new, original, and ornamental Design for a Decorative Cover for Bottles, of which the following is a specification, reference being had to the accompanying drawing, forming a part thereof:

Fig. 1 is a side elevational view of a decorative cover for bottles showing my new design;

Fig. 2 is a front elevational view; and

Fig. 3 is a top plan view thereof.

What I claim is:

The ornamental design for a decorative cover for bottles, as shown.

FRANZ KOENIGSBERGER.
